UNITED STATES PATENT OFFICE.

JOHN AHLBY, OF BERGLAND, MICHIGAN.

TIE AND RAIL HOLDER.

1,401,935.

Specification of Letters Patent. Patented Dec. 27, 1921.

Application filed April 23, 1921. Serial No. 463,854.

To all whom it may concern:

Be it known that I, JOHN AHLBY, a citizen of the United States, residing at Bergland, in the county of Ontonagon and State 5 of Michigan, have invented certain new and useful Improvements in Tie and Rail Holders, of which the following is a specification.

This invention relates to rail laying equipment and the object is to provide a simple, practical and efficient device for holding railway rails in steady and proper position against a tie while spikes are being driven into the tie. Further objects will be disclosed in the course of the following specification and are illustrated in the accompanying drawing, in which:

Figure 1 is a top view of my device, illustrating its application to a tie where two 20 rails are about to be spiked thereto.

Fig. 2 is a sectional view of the line 2—2 in Fig. 1.

Fig. 3 is a rear elevation of the holder as used when spiking one rail only.

Referring to the drawing by reference numerals 4 designates rails which are to be spiked to ties 5. When two rails are to be spiked as shown in Figs. 1 and 2, a shaft 6 has flanged wheels 7 at its ends which are 30 adapted to roll on the rails 4 from one tie to another. Slidable on the shaft 6 is a wheel 8, having a bail 9 adapted to hold a long hand lever 10, the latter resting on said wheel when pressure is brought to bear down 35 on it. Said wheel 8 is also flanged so that it will guide properly on the rail when only one rail is being spiked (see Fig. 3), in which event the shaft 6 and wheels 7 are removed.

The lower end of the lever is provided with two lugs 11, the outer ends of which are as far apart as the width of the lower flange of the rail 4. To said outer ends are pivotally secured a pair of tongs 12, 13^a whose lower 45 ends are provided with prongs 14^a adapted to grip under the tie 5. To the upper end of the tong 12 is pivotally mounted a curved bar 13 having a weight 14 at its moving or swinging end. The curved or main part of

said bar is slidable in a perforated extension 15 of the tong 13.

In the operation and use of the device when two rails are to be spiked the complete device, as shown in Figs. 1 and 2, is rolled along from place to place on the rails. The ties to be spiked are gripped by the tongs 12, 13^a which are held together by the weight 14. When pressure is then brought to bear down on the handle 10 it is obvious that the rails and tie will be firmly clamped together, in which condition they may be spiked properly together. The spiking of a single rail is accomplished by removing the shaft 6 and its wheels 7 and placing the wheel 8 on the rail (see Fig. 3). In this event the tongs are far enough apart to straddle the rail, and will grip over the sides of the tie, thus leaving room for spiking it on top.

It is further understood that suitable 70 modifications may be made in the form and structure of this invention, provided, however, that such modifications come within the spirit and scope of the appended claims.

Having now therefore fully shown and described my invention what I claim to be new and desire to protect by Letters Patent is:

1. A device of the class described consisting of a hand lever adapted to fulcrum on a rail, a pair of tongs pivotally mounted on the end of the lever and adapted to grip under a tie placed under the rail, and a curved bar pivotally connected to the upper end of one of the tongs, said bar being slidable in the upper end of the other tong.

2. A device of the class described consisting of a hand lever adapted to fulcrum on a rail, a pair of tongs pivotally mounted on the end of the lever and adapted to grip under a tie placed under the rail, a substantially U-shaped bar pivotally secured at one end to the upper end of one of the tongs, and a weight at the other end of the bar, said bar being slidable in the upper end of the other tong.

In testimony whereof I affix my signature.

JOHN AHLBY.
